FLOOR COVERING

George R. Cunningham, Grosse Pointe Park,
Mich., assignor to National Automotive Fibres,
Inc., Detroit, Mich., a corporation of Delaware

Application November 12, 1938, Serial No. 240,199

3 Claims. (Cl. 154—49)

The present invention relates to a rug and more particularly to a rug intended for use in an automotive vehicle which is decorated and protectively bound in a novel manner.

It is an object of the present invention to provide a rug or carpet having its edges bound by decorative means.

It is a further object of the present invention to provide a rug or carpet having decorative bands of formed material extending thereacross.

More specifically it is an object of the present invention to provide a rug or carpet having its ends bound with decorative strips of vulcanized rubberous material.

Other objects of the invention will be apparent as the description proceeds and when taken in conjunction with the accompanying drawing, and wherein:

Fig. 1 is a plan view of a rug or carpet made according to the present invention;

Fig. 2 is a fragmentary section on the line 2—2, Fig. 1;

Fig. 3 is a fragmentary section on the line 3—3, Fig. 1; and

Fig. 4 is a fragmentary sectional view illustrating a die adapted to form the edge binding disclosed herein.

The present invention contemplates the manufacture of rugs or carpets for floor covering in automotive vehicles. In the past such rugs or carpets have been subject to the criticism that the edges are apt to ravel or as an alternative expensive and unsightly edge binding was employed.

According to the present invention rugs or carpets for floor covering in automotive vehicles are simultaneously decorated and edge bound by permanently attaching strips of decorative material thereto. Preferably these strips of material are rubberous and are permanently vulcanized to the floor covering.

In Fig. 1 is illustrated a floor covering 10 having its edges bound with strips of decorative material 11 and also provided with two intermediate decorative strips or bands 12.

Intermediate strips or bands 12, as seen in Fig. 2, comprises a flat strip of material, which in the preferred embodiment is a vulcanized rubberous composition. In order to impart a decorative effect thereto, the strip 12 is formed during or prior to vulcanization in a predetermined pattern. In the embodiment illustrated I have shown a pair of parallel beads 13 extending lengthwise of the strip.

The edges of the floor covering have a decora-

tive binding strip 11 vulcanized thereto. This strip 11, indicated best in Fig. 3, extends slightly beyond the edge of the floor covering as indicated at 14, and in addition has decorative beads 15 or the like 16 formed thereon.

In manufacturing the improved floor covering a flat strip of uncured rubberous material is placed along the edge of the floor covering. The assembly is then placed in a die such as 10 indicated in Fig. 4. This die comprises a base or plate 16 which is preferably flat and a heated die 17 formed with recesses 18 adapted to mold the rubberous material into the beads 15 previously referred to. In addition the die 17 is provided with sharp knife edges 19 and 20 for the purpose of cutting any projecting portion of the strip of rubberous material. The die member 17 and if desired the plate 16 are heated by suitable means, and the application of heat and pressure serves to vulcanize the strip 11. This vulcanization causes the strip 11 to retain its molded form and in addition results in a permanent bond between the strip and the floor covering.

25 It will be appreciated that any projecting portions of rubberous material which extend beyond the knife edges 19 and 20 will not be subjected to heat and accordingly will not be vulcanized to the floor covering. It will therefore be possible to remove such projecting portions leaving the vulcanized strip with a ruled edge.

30 As will be understood, the rubberous material during its vulcanization becomes softened with the result that the pile of the floor covering becomes imbedded to some extent in the lower portion of the rubberous material. At the same time the rubberous material is caused to flow through the pile so that the bond between the rubberous material and the body portion of the floor covering is effected through the pile formation.

35 It will be understood that the decorative bands 12 shown in section in Fig. 2 are formed substantially in the same manner as the edge bindings 11. For this purpose a die assembly corresponding to that shown in Fig. 4 will be employed.

40 The strips of rubberous material are relatively thin and as shown in Figs. 2 and 3 their upper surface is below the top surface of the pile. This contributes materially to the effectiveness of the decoration, as will be readily apparent.

45 The foregoing detailed description has been given for clearness of understanding only, and

no unnecessary limitations should be understood therefrom, but the appended claims should be construed as broadly as permissible in view of the prior art.

What I claim as my invention is:

1. A woven pile floor covering having a base fabric and a pile, an edge binding for said floor covering comprising a rubber strip overlying and extending beyond the edge of said floor covering, said strip holding down the pile therebeneath along the edge of said floor covering and being vulcanized through said pile to said base fabric.

2. A woven pile floor covering having a base fabric and a pile, an edge binding for said floor covering comprising a rubber strip overlying and extending beyond the edge of said floor covering, said strip holding down the pile therebeneath along the edge of said floor covering and

being vulcanized through said pile to said base fabric, the extending portion of said rubber strip extending downwardly along the edge of said base fabric to provide an extending flap adapted to rest on the floor.

3. An edge binding for a woven pile floor covering having a base fabric and pile thereon comprising a strip of rubber overlying the edge of said floor covering having the pile therebeneath matted down and embedded therein and being vulcanized through said pile to the base fabric, a portion of said strip extending downwardly along the edge of said base fabric to the bottom thereof, said strip provided with a flexible flap extending outwardly from said portion, the bottom of said flap being in the plane of the bottom of said base fabric.

GEORGE R. CUNNINGTON.
